(57) CLAIM

We claim the ornamental design for an abrasion device with abrasive tip, as shown and described.

DESCRIPTION

FIG. 1 is an isometric view of an abrasion device with abrasive tip with the tip removed for ease of illustration; FIG. 2 is a side elevation view, the opposite side elevation being a mirror image thereof;

FIG. 3 is a top elevation view;

FIG. 4 is a bottom elevation view;

FIG. 5 is a back elevation view;

FIG. 6 is a front elevation view;

FIG. 7 is an isometric view of the tip of the abrasion device with abrasive tip with other portions of the device not shown for ease of illustration;

FIG. 8 is a side elevation view; the opposite side, front and back elevations being mirror images thereof;

FIG. 9 is a top elevation view;

FIG. 10 is a bottom elevation view;

FIG. 11 is an isometric view of an abrasion device with abrasive tip shown fully assembled; and,

FIG. 12 is a side elevation view, the opposite side elevation being a mirror image thereof.

The broken lines shown in FIGS. 1-6 and 11-12 illustrate portions of the abrasion device with abrasive tip that form no part of the claimed design.

1 Claim, 7 Drawing Sheets
